CLAIM

The ornamental design for a faucet as shown and described.

DESCRIPTION

FIG. 1 is a perspective view of the claimed design; FIG. 2 is a side view of the claimed design shown in FIG. 1;

FIG. 3 is another side view of the claimed design shown in FIG. 1;

FIG. 4 is a front view of the claimed design shown in FIG. 1;

FIG. 5 is a rear view of the claimed design shown in FIG. 1;

FIG. 6 is a top view of the claimed design shown in FIG. 1; and,

FIG. 7 is a bottom view of the claimed design shown in FIG. 1.

The ornamental design which is claimed is shown in solid lines in the drawings. The broken lines in the drawings are for illustrative purposes only and form no part of the claimed design. Broken lines formed of unequal length dashes (i.e., dash-dot) define bounds of the claimed design.
